UNITED STATES PATENT OFFICE.

WILLIAM E. DENNIS, OF FAR ROCKAWAY, AND HARRY S. BRETON, OF LONG ISLAND CITY, NEW YORK, ASSIGNEES, BY MESNE ASSIGNMENTS, TO AMERICAN AEROCAR HOLDING CORPORATION, OF RICHMOND HILL, NEW YORK.

FLYING-MACHINE.

1,206,680.

Specification of Letters Patent. Patented Nov. 28, 1916.

Application filed August 26, 1910. Serial No. 579,114.

To all whom it may concern:

Be it known that we, WILLIAM E. DENNIS and HARRY S. BRETON, citizens of the United States, residing at Far Rockaway and Long Island City, respectively, in the county of Queens and State of New York, have invented certain new and useful Improvements in Flying-Machines, of which the following is a specification.

- 10 This invention relates to flying machines of the heavier-than-air type, in which the machine is supported in flight by the dynamical reactions of the air upon the supporting surface or surfaces thereof.
- 15 One of the objects of the invention is to provide a machine of this type in which the major portion of the weight of the load, *i. e.*, that of the motor, drive gearing, gasoline or other fuel, the pilot, passengers etc., are arranged below the supporting surface and is so disposed as to provide a low dead center or center of gravity operating to oppose a resistance to the tilting of the machine in any direction in flight, whereby the stability 20 of the machine is increased through the resultant inherent automatic balancing action secured and greater safety in the operation of this class of machines insured.

A further object of the invention is to provide a novel construction of the supporting surface or surfaces by which, in the event of an excess downward and forward tilting of the machine or descent at too sharp an angle, the necessary angle of incidence will still be 35 presented to sustain the machine and prevent any possibility of loss of the fore and aft balance and overturning of the machine.

A further object of the invention is to provide a novel construction of horizontal 40 rudders constructed to secure a quick and effective action of the air thereon for sensitive steering and balancing movements of the machine.

A further object of the invention is to provide a novel construction and arrangement 45 of stabilizing and controlling wings which are adjustable to increase or decrease the supporting area, as occasion may require, whereby the flow of lateral currents of air 50 to the associated supporting surface is regulated, the pressures properly controlled and distributed, and excess pressures prevented.

Still further objects are to provide resilient tips at the rear edge of a main plane or

supporting surface which permit of an air 55 shedding action similar to the flexible tip feathers of the wings of a bird; to provide novel and easily controlled steering mechanism; to provide a more efficient and safer type of propeller; and to provide a novel 60 general construction and arrangement of parts whereby strength, durability and rigidity of structure are secured.

In the accompanying drawings, we have shown the application of our invention to a 65 biplane machine, but it will, of course, be understood that the essential features of the invention may be embodied in monoplanes, triplanes or other species of machines of the heavier-than-air class, and hence we do not 70 limit the invention in this particular.

In the said drawings: Figure 1 is a top plan view of a flying machine embodying the novel features of our invention. Fig. 2 is a bottom plan view of the same. Fig. 3 is 75 a view in side elevation. Fig. 4 is a vertical longitudinal section. Fig. 5 is a vertical transverse section. Fig. 6 is a detail view of one of the wing tips. Fig. 7 is a detail section through the controlling mechanism. 80 Fig. 8 is a detail section on the line 8—8, Fig. 7. Fig. 9 is a vertical section through one of the slotted guide standards.

Referring to the drawings, 1 designates the main frame or fusilage of the machine, 85 which is in the form of a car or suitable sub-structure arranged wholly below the supporting surfaces, and which comprises longitudinal bars 2, connecting cross bars 3, and one or more platform portions 4, on which 90 are mounted the pilot's seat 5, driving motor 6, passengers' seats 7 and the steering gear operating and other controlling devices hereinafter described. From this frame extend uprights 8, laterally projecting inclined stay 95 bars 9, and V-shaped supporting brackets 10, to which uprights and brackets the gasoline or fuel tanks 11 are secured in any suitable manner.

Arranged above the main frame or fusilage 100 are the main planes or supporting surfaces 12 and 13, each comprising front and rear frame bars 14, and cross pieces 15 and bowed intermediate cross pieces or ribs 16, to which are attached a suitable fabric covering 17. The planes are connected and held in spaced relation by the usual struts 18, and the frame of the lower plane is suit-

ably fastened to the uprights 8, stay bars 9 and brackets 10, whereby the planes are supported from the main frame. The body portions of the respective planes are co-extensive in size or supporting area, and said planes extend lengthwise, as usual, transversely to the line of flight, the ribs 16 being bowed to a desired degree to give the necessary fore-and-aft concavo-convex curvature to the body of each plane for the effective dynamical reactions of the air thereon to support the machine in flight. Each plane has a front longitudinal edge or wing 19 projecting beyond its frame portion and upwardly and forwardly curved to impart a concavo-convex contour thereto, the convex side of said extension edge or wing facing downward. This extension edge, which is reinforced from the struts 20 by stay wires 20, increases the lift of the supporting surface and normally lies above the plane of that portion of said surface which presents the normal angle of incidence for aerodynamic sustension. If, however, the machine should pitch forward to an excess degree, or be guided downward in flight at an abnormally acute angle, the convex surfaces of the extension edges or wings will present a new and advanced angle of incidence for the impact of the air, whereby the machine will be supported and prevented from turning over, allowing the pilot to regain complete control.

Projecting from the front and rear of the machine are head and tail frames 21 and 22, respectively, which differ in the fact that the latter is materially longer than the former, but are otherwise substantially the same in construction, so that a description of one will suffice in the main for both. Each of these frames comprises a pair of upper parallel bars 23 secured at their inner ends to the frame of the upper main plane and connected by cross bars 24, a pair of upwardly and outwardly inclined lower bars 25 secured at their inner ends to the main frame and connected by cross bars 26, and uprights 27 uniting the upper and lower bars at each side of the frame. These frames carry suitable bearing brackets for front and rear sets of wheels 28 and 29, which support the machine when it is at rest and run along the surface of the ground in launching and landing. Wheels or rollers 30 are also provided upon the rear of the tail frame which provide for the running support of the machine when tilted at the instant of ascent from the ground, thus guarding the tail frame from injury.

60 Mounted upon the head frame to swing vertically upon a horizontal axis is a front horizontal rudder 31, preferably formed of a pair of superposed planes movable in unison, and mounted to swing similarly upon the tail frame is a rear horizontal rudder

32, preferably composed of a single plane. Crank arms 33 and 34 are suitably connected with the horizontal shafts of the respective rudders and are coupled by links 35 to a suitably guided, longitudinally extending rack bar 36, whereby the two rudders are adapted to be simultaneously adjusted. The teeth of the rack bar 36 mesh with a gear 37 on a transverse shaft 38 journaled on the frame of the upper main plane and which carries a miter pinion 39 meshing with a miter gear 40 on the upper end of a hollow shaft 41. The shaft 41 is journaled on a stationary inclined rod or shaft 42 and in brackets 43, 44, fixed, respectively, to the main frame and upper main plane, and is provided with a hand wheel 45, by which it may be turned to adjust the rudders through the above-described gearing in an obvious manner. The rod or shaft 42 is fixed at its upper end to the frame of the upper main plane and at its lower end to a supporting bracket 42^a in any suitable manner. The lower end of the rod 42 has journaled thereon outer and inner concentric shafts 46 and 47 provided with hand wheels 49 and 50, the shaft 46 being also provided with oppositely extending tiller arms 51 and 52, while the shaft 47 carries drums 53 and 54. On the respective hollow shafts are toothed wheels 41^a, 46^a and 47^a, adapted to be engaged by spring pressed pawls 41^b, 46^b and 47^b pivoted upon the bracket 43, whereby said hollow shafts may be locked against rotary movement and released for turning movement, as occasion requires. The horizontal rudder planes are concavo-convexly curved fore and aft like the main supporting planes and are respectively provided with upturned concavo-convex front edges 31^a and 32^a having their convex surfaces facing downward, so that said rudders normally act as auxiliary supporting surfaces, and, when adjusted to an ascensional position, will present said curved front edges at such an angle as to secure a materially increased pressure of the air thereon over rudders of ordinary construction thereby augmenting the lifting capacity of the rudders and securing a more rapid and sensitive elevating action and longitudinal balancing control. On the tail frame is a vertical rudder 55 carried by a vertical shaft 56 to which are fixed crank arms 57 and 58, said arms being connected by wires 59 and 60 to the tiller arms 51 and 52, so that said rudder may be adjusted for lateral steering by turning the wheel 45.

It will be observed that the curvature of the horizontal rudders corresponds to that of the main planes, and that the body portion of each plane and rudder is arranged wholly below the plane of its upturned front edge and is curved downwardly

and rearwardly from its point of junction with such upturned edge. Hence the rudders serve as smaller auxiliary supporting surfaces whose body portions present the 5 same angle of incidence as the main planes when the machine is traveling parallel with the earth's surface, while under such conditions, the upturned edges of both the planes and rudders are arranged at a negative 10 angle. By this relative arrangement of the body portions of the planes and their upturned edges the latter are prevented from deflecting the air downward and inhibiting its proper dynamical reaction against the 15 surfaces of the planes when the machine is traveling horizontally or climbing, but are brought into play to provide advanced angles of incidence when any excess forward tilting of the planes or rudders occurs, whereby the center of pressure will 20 be changed to a degree corresponding to the change in the center of gravity to maintain the longitudinal stability of the machine.

Extending from the sides of the machine 25 are outriggers 61, each comprising inclined bars 62 connected with the frame of the lower main plane, a cross bar 63 connecting the outer ends of said bars, and bars 64 connecting the bar 63 with the adjacent struts. Leading upwardly from the respective cross bars 63 of the two outriggers are curved slotted guide standards 65 which extend above the top of the upper main plane and are stayed from the frame of said 35 plane by braces 66. Pivotaly mounted at their inner ends upon the ends of the upper main plane 12, as at 67, are stabilizing and controlling wings 68 each having substantially the shape of a bird's wing, that 40 is, tapering longitudinally to their outer ends or tips and being of concavo-convexly curved outline both longitudinally and transversely. Each wing consists of a suitable frame structure and fabric covering 45 and has a guide arm 69 at its outer end which fits and travels in the slot of the adjacent guide standards. These wings increase the length of the upper supporting surface relatively to the length of the lower 50 supporting surface, thus giving increased efficiency. Wound intermediately about the drums 53 and 54 of the shaft 47 are endless ropes or other like flexible connections 55 and 71, the stretches of the respective ropes extending over or through suitable guides 72 to the respective standards 65, each rope having one of its ends extending upwardly to the guide arm 69 of the adjacent wing and its opposite end passing through guides 60 73 to the top of the associated standard 65 and thence extending downward and attached to the arm 69, so that the two stretches of the rope will be alternately wound and unwound upon the rotation of 65 the coöperating drum in reverse directions,

to respectively raise and lower the wing. The two ropes are so wound upon their respective drums that when the shaft 47 is turned in one direction both wings will be simultaneously and coördinately lowered, 70 while when said shaft is turned in the reverse direction both wings will be simultaneously and coördinately raised, as will be readily understood. The wings are normally arranged in a substantially intermediate position, as shown in full lines in the drawings, when the machine is in straight flight, in which position, owing to their described curvature, they present the necessary angle of incidence to the air for supporting effect and gradually incline outwardly and upwardly above the plane of the main plane 12. Owing to the tapering form of these wings cross currents of air striking the same will be broken up or 80 divided and partially shed and partially employed for supporting action, said wings distributing a portion of the air of such currents to the main plane 12 and deflecting the remainder rearwardly, thus preventing 90 the action of any excess pressure of air upon either end of said main plane and thereby preserving the lateral balance. In other words, the wings, while operating as lateral auxiliary supporting surfaces, shed any excess volume or pressure of air which falls thereon and act as guards to prevent the passage of any abnormal volume or pressure of air to the underside of the main plane 12. By depressing the wings their supporting action 95 will be increased and they will augment the lifting capacity of the machine, and by elevating them their air shedding action will be increased, thus diminishing the superficial effective area of the supporting surface of 1 the machine. Hence by adjusting the wings in one direction the ascent of the machine will be facilitated and its sustentation power increased, while by adjusting the wings in the reverse direction the speed of descent 100 of the machine may be increased without tilting the horizontal rudders to an objectionable angle. The value and importance of this part of our invention will accordingly be appreciated.

In connection with each wing 68, we preferably employ an auxiliary wing 68^a pivotally mounted to swing vertically upon the adjacent struts 18 of the main frame, said auxiliary wing being of somewhat smaller size or area than the wing 68 and arranged below the same so as to extend on a line centrally between the supporting surfaces when disposed in horizontal position. The auxiliary wing 68^a is connected at its outer end 115 by a link 68^b with the superposed main wing 68 to move in unison therewith, and has its inner end arranged for movement between the adjacent ends or margins of the supporting surfaces. Each auxiliary wing con-

- forms substantially in longitudinal and cross sectional contour with the main wing and coöperates therewith to further increase or decrease the supporting area, as occasion requires in the control of the machine. The auxiliary wings at the opposite sides of the machine further promote and increase the lateral rigidity or stability of the machine as a whole, as will be readily understood.
- 10 Arranged at the rear of the main plane 12, on opposite sides of the longitudinal center of the machine, are series of wing tips 74, each approximately of semi-elliptical form and comprising a suitable frame and a fabric covering. These tips extend longitudinally along the rear edge of the plane 12, and are hinged thereto to swing vertically and held normally depressed by springs 75, which permit said tips to yield 20 upwardly under a determined air pressure. The tips of each series are spaced a slight distance to provide intervening air spaces to permit at all times the shedding or release of a proportion of the air, thus simulating the normal air shedding action of the edges of the wings of a bird. These tips further increase the area of the supporting surface of the main plane and are adapted to yield upwardly under excess pressure of 30 air to prevent the undue retention of air beneath the plane, while normally assisting in pocketing and increasing the dynamical reactions of the air upon the surface of the plane. Through such automatic pocketing and air shedding actions the supporting capacity of the plane 12 is materially enhanced over a plane of ordinary construction and of the same surface area but unprovided with resilient wing tips of this character.
- 40 Heretofore it has been the practice to mount the load weight wholly or partially above the supporting surface, and in all biplanes and other multiplanes with which we are familiar the load weight has invariably 45 been placed above the lower supporting plane. As a result, the dead center or center of gravity of the machine is placed at a relatively high point, to which is due in whole or in part the instability of even the 50 most successful machines, and particularly those of the biplane, triplane or other multiplane type. We overcome and avoid this objection by disposing the entire load weight or at least a balancing portion or proportion 55 thereof upon a substructure wholly below the supporting surface as a whole, *i. e.*, beneath the lower plane in a biplane or other multiplane structure, whereby the dead center or center of gravity is lowered to the 60 safest maximum limit, and such load weight therefore operates to oppose a resistance to the tilting of the machine in any direction in flight, whereby the stability of the machine is increased through the resultant inherent automatic balancing action secured

and greater safety in flight insured. By "load weight" we mean the aggregate weight of the motor, drive gearing, fuel, pilot, passengers and other appliances or freight, exclusive of the sustentation parts of the apparatus, and by "supporting surface" we mean such sustentation parts, irrespective of the number or arrangement of flotation planes or equivalent surfaces used. Our invention, as a matter of fact, contemplates 75 the broad idea of placing the load weight below the supporting surface however the same may be constructed or disposed. By "balancing portion or proportion of the load weight" we mean any amount thereof 80 sufficient to perform the function of a balancing or stabilizing medium. The term "load weight" is therefore held to include all or any portion of the weight necessary or suitable for such purpose. 85

From the foregoing description, taken in connection with the accompanying drawings, the mode of launching, landing and controlling the machine in flight will be readily understood by those versed in the 90 art without further explanation.

It will, of course, be understood that whenever necessary the parts of the machine may be reinforced and stayed by the usual guy wires 76. It will also be understood that the upper plane 12 with its appurtenances may be employed as the supporting surface in a monoplane structure. The propeller or propellers for driving the machine may be constructed and arranged 95 in any suitable manner. In practice we preferably employ a single propeller embodying a shaft 77 carrying two sets of blades 78 and 79, so that if the blades of either set are broken the blades of the remaining set will continue to act and will be sufficient for propulsion. The shaft 77 is shown as journaled on cross bars 80 and 81 and a bracket 82 supported by two of the rear struts and adjacent uprights of the tail frame, but any other mode of mounting may be employed and in practice the propeller may be driven from the motor by any suitable type of gearing. 100

We claim:

1. In a flying machine, the combination of a main frame, superposed supporting surfaces carried thereby, a carriage rigid with the main frame and arranged wholly below the lower supporting surface, propelling and steering devices also mounted upon the main frame, a driving motor, an aviator's seat and fuel carrying means all mounted directly upon the carriage and supplementing the weight thereof, whereby the carriage and its load weight serves as a weighted stabilizing pendulum, longitudinally tapered and longitudinally and transversely curved wings mounted to swing vertically on fore and aft axes at the ends 105

of the upper supporting surface, a control device on the carriage, and connections between said control device and wings for simultaneously and coördinately adjusting 5 said wings in the same direction either upward or downward and at an equal angle of incidence to said supporting surface.

2. In a flying machine, the combination 10 of a main frame, a supporting plane carried thereby, braces fixed to said plane, wings pivoted to and extending outwardly laterally from the lateral margins of the main plane, said wings being longitudinally and transversely curved, arcuately curved guides 15 fixed to said main frame and braces, guide members on the free edges of the wings slidably engaging said guides, a controlling device, and connections between said guide members on the wings and the said controlling device for vertically moving said wings 20 to like degrees in the same direction simultaneously.

3. In a flying machine, the combination 25 of a main frame, a supporting plane carried thereby main wings pivoted to and extending outward laterally from the lateral margins of the supporting main plane, said wings being longitudinally and transversely curved, supplemental wings pivotally mounted 30 below the main wings and extending both beneath and laterally beyond the lateral margins of the supporting plane, connections between each main wing and the underlying supplemental wing to effect their movement in unison, a controlling device, and connections between said controlling device 35 and the pairs of wings for vertically moving both pairs of wings to like degrees in the same direction simultaneously.

4. In a flying machine, a frame structure, superposed supporting surfaces, an upwardly and rearwardly inclined rod fixed at its lower end to the frame structure and at its upper end to the upper supporting 45 surface, a series of hollow concentric control shafts mounted on said rod and each provided with an operating member and a ratchet wheel, a plurality of governing elements, connections between the respective 50 shafts and the governing elements, and locking devices on the frame to engage said ratchet wheels.

5. In a flying machine, the combination 55 of a main frame, a pair of supporting planes carried thereby, main wings pivoted to and extending outward from the lateral margins of the upper supporting plane, said wings being longitudinally and transversely curved, guiding means for the free ends of 60 said wings, a supplemental wing pivotally mounted below each main wing on a line between the supporting planes and extending inwardly and outwardly beyond the vertical plane of the lateral margins of said 65 supporting planes, a connection between

each main wing and the underlying supplemental wing coupling said wings for movement in unison, a controlling device, and connections between said controlling device and the pairs of wings for vertically moving both pairs of wings to like degrees in the same direction simultaneously. 70

6. In a flying machine, a supporting surface, a series of closely arranged semi-elliptical wing tips hinged to the rear edge of 75 said supporting surface, said wing tips having their adjacent side edges spaced apart to provide narrow intervening air-gaps, and springs resiliently connecting said wing tips with the supporting surface for yielding by holding said tips in the plane of said surface and permitting said tips to have independent upward and downward flexing movement to like or different degrees. 80

7. In a flying machine, a supporting surface, a plurality of closely arranged, spaced, semi-elliptical wing tips disposed along and hinged to the rear edge of said supporting surface, and coiled springs terminally fixed to the supporting surface and wings for 90 yieldingly holding the tips in the plane of said surface and permitting said tips to have independent upward and downward flexing movement to like or different degrees. 95

8. In a flying machine, a horizontal rudder, a crank arm connected therewith, a pair of spaced guides, a bar slideable at its ends in said guides and provided between its ends with a series of rack teeth, a link 100 connecting said crank arm with an end of the rack bar, a transverse shaft, a gear thereon meshing with the teeth of the rack bar, an upright shaft in gear with said transverse shaft, means for rotating said 105 upright shaft, and means for locking said upright shaft in adjusted position.

9. In a flying machine, a frame, superposed supporting surfaces, vertically movable main wings at the ends of the upper 110 supporting surface, vertically movable supplemental wings hinged in rear of their transverse centers in line with the ends of the supporting surfaces, said supplemental wings having their shorter ends extending 115 between said supporting surfaces and their longer ends projecting beyond said surfaces and beneath said main wings, connections coupling the pairs of main and supplemental wings for movement in unison, and 120 means for operating both sets of wings simultaneously and coördinately in the same direction.

10. In a flying machine, a supporting surface, vertically movable longitudinally tapered wings and longitudinally and transversely curved wings at the opposite ends of said surface, said wings being mounted to swing on horizontal fore and aft axes and normally inclined to the plane of said 125 130

surface, and means positively coupling the wings for simultaneously and coördinately adjusting said wings in the same direction either upward or downward from their normal position above or below the plane of the supporting surface and at an equal angle of incidence with relation to the supporting surface.

11. In a flying machine, a supporting surface, vertically movable, upwardly and outwardly angled wings extending longitudinally beyond the lateral margins of said surface and tapering to tips at their outer extremities, said wings being longitudinally and transversely curved and hinged at their inner edges to swing on horizontal fore and aft axes, and means positively coupling the wings for simultaneously and coördinately adjusting said wings in the same direction either above or below the supporting surface and at an equal angle of incidence with relation to the plane of said surface.

12. In a flying machine, superposed supporting surfaces, vertically movable main wings at the ends of the upper supporting surface, vertically movable supplemental wings arranged on a line between and extending beyond the supporting surfaces, the sets of wings being connected for movement in unison, and means for operating both sets simultaneously and coördinately in the same direction.

13. In a flying machine, a supporting surface, vertically movable wings normally inclined upwardly and outwardly and extending longitudinally from the opposite ends of said surface, said wings being mounted to swing on horizontal fore and aft axes, and longitudinally tapered and longitudinally and transversely curved, and means positively coupling the wings for simultaneously and coördinately adjusting said wings in the same direction either upward or downward above or below the plane of the supporting surface, and at an equal angle of incidence with relation to said supporting surface.

14. In a flying machine, a main frame, a supporting surface, outriggers at the sides of the main frame, curved guides extending upwardly therefrom and connected with the supporting surface, normally outwardly and upwardly inclined longitudinally and transversely curved vertically movable wings at the ends of the supporting surface having guide members at their ends engaging said guides, and means for simultaneously and coördinately adjusting said wings either upward or downward at an equal angle of incidence with relation to said supporting surface.

15. In a flying machine, a main frame, a supporting surface, a stationary shaft extending between and fixed to said frame

and surface, horizontal and vertical rudders, normally inclined wings at the ends of the supporting surface, movable simultaneously and coördinately in the same direction above or below the plane of said surface, devices for operating the rudders and wings including a plurality of rotary members concentrically journaled on said shaft, and devices for locking the respective rotary members from rotation.

16. In a flying machine, the combination of a main frame, superposed supporting surfaces having body portions uniformly concavo-convexly curved fore and aft and having upturned front edges and down-turned rear edges, superposed horizontal rudders arranged approximately in the horizontal plane of said surfaces and conforming in contour thereto, and means for adjusting said rudders.

17. In a flying machine, superposed supporting surfaces, vertically movable main wings at the ends of the upper supporting surface, vertically movable supplemental wings arranged on a line between and extending beyond the supporting surfaces, links connecting the sets of wings for movement in unison, and means for operating both sets simultaneously and coördinately in the same direction.

18. In a flying machine, the combination of a main frame, a supporting plane carried thereby, braces fixed to said plane, wings pivoted to and extending outward from the lateral margins of the main plane, arcuately curved slotted guides fixed to said main frame and braces, guide members on the free edges of the wings slidably engaging the slots in the guides, a controlling device, and connections between said guide members on the wings and the said controlling device for vertically moving said wings to like degrees in the same direction simultaneously.

19. In a flying machine, a supporting surface, vertically movable ailerons at the ends of said surface, said ailerons being longitudinally tapered and longitudinally and transversely curved, guides extending above and below the plane of the supporting surface, guide members on the ailerons slidably engaging said guides, direction members on said guides, a looped cable threaded through the direction members on each guide and forming up and down pull stretches connected with the aileron, and a controlling device to which the free ends of the stretches of the cable are connected for simultaneously adjusting said ailerons.

20. In a flying machine, a main frame, a supporting surface, a stationary shaft extending between and fixed to said frame and surface, horizontal and vertical rudders, stabilizing wings, devices for operating the rudders and wings, including a plurality of ro-

tary members concentrically journaled on said shaft, and devices for locking the respective rotary members from rotation.

21. In a flying machine, the combination 5 of a supporting surface, a carriage rigid with and arranged wholly below said supporting surface, means whereby said carriage is adapted to carry the load weight and form a pendulum to gravitatively maintain 10 the balance of the machine, a control device upon the carriage, longitudinally tapered, longitudinally and transversely curved wings mounted to swing vertically on fore and aft axes at the ends of said supporting 15 surface, and connections between said wings and the control device for positively, simultaneously and coördinately adjusting said wings either upwardly or downwardly in unison at an equal angle of incidence above

or below the plane of the supporting surface.

22. In a flying machine, a supporting plane having an upturned front portion, a downturned rear portion and a body portion extending on a downward curvature between 25 said portions and lying entirely below a horizontal line passing through the extreme front edge of the upturned front portion, the said upturned front portion being arranged at a relatively greater angle of incidence 30 than the remainder of the plane.

In testimony whereof we affix our signatures in presence of two witnesses.
